BUTTON LOOP

George Henry Elwell, New Haven, Conn., assignor
to Eastern Tool and Manufacturing Company,
Bloomfield, N. J., a corporation

Application February 6, 1943, Serial No. 474,955

4 Claims. (Cl. 24—224)

This invention relates to button loops adapted to be clipped over a button to support a garment upon which the button is attached, and more particularly to that class of button loops of the rigid type.

The objects of the invention are to provide for the rigid type of button loop a certain resiliency; and to provide for such button loop a constricted throat portion adapted to expand momentarily for the passage therethrough of the shank of a button.

With reference to the accompanying drawing, the Figure 1 is an upright view of the device in normal condition before admitting the shank of a button into the constricted throat portion; the Figure 2 is a side view of the device; the Figure 3 is a view similar to that of the Figure 1, but illustrating the shank within the expanded throat portion; and the Figure 4 is a fragmentary perspective view on an enlarged scale of a detail part.

With particular reference to the accompanying drawing, the button loop comprises the wire structure having the upper horizontal bar 2 of the strap loop 1 and the horizontally aligned and relatively spaced lower bar sections 3 and 4. Integrally depending from both of the bar sections 3 and 4 are the companion arms X formed together to provide the button-receiving loop 5 and the button-retaining loop 6, intercommunicated by means of the constricted throat portion 7, the wire terminals 8 of the arms X meeting at an inclined angle to provide the seat 9 for the shank 10 of an inserted button (not illustrated), the extremities 11, of the said terminals 8, each being flattened, overlapped, bored and secured, one to the other, by means of the pivot pin 12. The pivot pin 12 is fitted into each of the bores or perforations 13 of which intersecting diameters are equal and with which each wire extremity 11 is alike provided for a simple pivotal connection thereof.

In operation, a button (not illustrated) is inserted within the button-receiving loop 5, and the shank 10 of the button having, for instance, an outside diameter of five-sixteenths of an inch, rests at the entrance of the constricted throat portion 7 having only an inside diameter of less than that of the outside diameter of the shank 10. By means of a slight manual urging, the shank 10 may be made to expand and pass through the constricted throat portion 7 and into the button-retaining loop 6 to become seated within the seat 9. However, when the shank 10 is urged to return through the constricted throat portion 7 and back into the button-receiving loop

5, it requires a slightly greater urging to accomplish that return.

This form of button loop, following as it does the well-known rigid type of structure, save for the pivoted wire extremities 11, relies for its patentability upon that pivotal peculiarity in giving a certain resiliency, to the otherwise usual rigidity, to make possible an easy passage of the button shank 10 one way therethrough and a slightly more difficult passage the opposite way, the reason for which is about to be explained with reference to the Figure 3.

Taking the pivot 12 as a center C, an arc A intersecting the interfacing curved portions of the relatively aligned horizontal bar portions 3 and 4, and a second arc A' intersecting the constricted throat portion 7, each arc A and A' defines opposite directions of yielding movements of the companion arms X due to their slight pivoting upon the pivot pin 12 as the shank 10, in its passage from the button-receiving loop 5, is urged through the constricted throat portion 7. In the Figure 3, the full lines of the companion arms X, intersected by the arcs A and A', illustrate the yielding position of said arms in contrast with their normal dotted position at such intersections, thereby intended to give an idea of said yielding movements of the companion arms X which results in an increased inside diameter of the constricted throat portion 7 sufficiently to permit an easy passage of the shank 10 therethrough. It will be noted however that while the urged passage of the shank 10 from the button-receiving loop 5 into the button-retaining loop 6 is coordinate with the downwardly inclined yielding movements of the relatively aligned horizontal bar portions 3 and 4, the return passage of the shank 10 from the button-retaining loop 6 to the button-receiving loop 5 is not so readily aided by the downwardly inclined yielding movements of the bar portions 3 and 4, but is somewhat opposed thereto, therefore, conforming to the best requirements of a button loop, the shank 10 is thus easily passed into the button-retaining loop 6 and is there held against accidental release by means of the slightly more difficult return passage through the constricted throat portion 7.

A further advantage of the improved button loop above described resides in the fact that it provides a semi-rigid structure having sufficient permanent resiliency to restore itself to a normal condition wherein the constricted throat portion 7 retains such an inside diameter as to normally prevent the passage of the shank 10 therethrough

unless momentarily expanded under an urged passage thereof.

I claim:

1. A button loop comprising a single length of wire providing in a common plane a strap loop and relatively associated button-receiving and button-retaining loops, said associated loops having between them in said plane a constricted throat portion, the free ends of the wire being relatively overlapped; a perforation, having intersecting diameters of equal length, with which each overlapped end is alike provided; and a pin fitted within said perforations to provide a simple pivotal connection therebetween.

2. A button loop comprising a single length of wire of which the central portion provides the upper bar of a strap loop having substantially parallel thereto aligned lower bar portions supporting relatively associated button-receiving and button-retaining loops in a common plane and having between them a constricted throat portion; flattened ends with which the wire is provided for relative overlapping thereof; a perforation having intersecting diameters of equal length with which each flattened end is alike provided; a pin fitted within said perforations to provide a simple pivotal connection therebetween; and a recessed seat within the retaining loop for the shank of a button.

3. A semi-rigid wire button loop structure including a strap loop having substantially parallel upper and lower bars and integral companion arms terminating in a button-retaining loop provided therein with a recessed seat for the shank of a button and accessible only by way of a constricted throat portion of said arms; a perforation with which each of the extremities of said arms is alike provided, intersecting diameters of each perforation being equal in length; and a pin fitted within said perforations to provide a simple pivotal connection therebetween permitting a slight rotary movement of said extremities about said pin; whereby the passage of a shank of a button through said constricted throat portion is assisted by said rotary movement.

4. A semi-rigid wire button loop including a strap loop and companion arms terminating in a button-retaining loop provided therein with a recessed seat for the shank of an inserted button; a constricted throat portion of said wire at the entrance of said retaining loop; a flattened portion with which each of the extremities of said arms is provided; a simple pivotal connection with which the flattened portions are relatively provided; whereby the passage of a shank of a button is made possible by said pivotal connection.

GEORGE HENRY ELWELL.
